UNITED STATES PATENT OFFICE

2,613,820

CAR COUPLING

Nathaniel Clark, Madison, W. Va.

Application September 20, 1948, Serial No. 50,175

1 Claim. (Cl. 213—189)

1

This invention relates to improvements in car couplings.

An object of the invention is to provide an improved form and construction of car coupling, especially adapted for use on mine cars.

Another object of the invention is to provide an improved car coupling for various types of cars which will automatically couple two cars when bumped together without any assistance from a brakeman or operator.

A further object of the invention is to provide an improved form and construction of car coupling which will automatically couple two cars together without assistance from a brakeman, and which may be readily released by lifting up on a release lever.

A still further object of the invention is to provide an improved car coupling which will be highly efficient in use, and relatively inexpensive to manufacture and produce.

Other objects will appear as the description proceeds.

In the accompanying drawings which form a part of this application,

Figure 1 is a side elevation of an end of a car equipped with the female portion of the improved car coupling;

Figure 2 is a side elevation of an end of a car equipped with the interengaging male portion of the improved car coupling;

Figure 3 is a bottom plan view of the car and female coupling portion shown in Figure 1;

Figure 4 is a bottom plan view of the car and male coupling portion shown in Figure 2;

Figure 5 is an end view of the car and female coupling portion shown in Figures 1 and 3;

Figure 6 is an end view of the car and male coupling portion shown in Figures 2 and 4;

Figure 7 is a perspective view of the pivotally supported locking cam arm;

Figure 8 is an enlarged detail view showing the shape of the outer end of the locking cam arm, and

Figure 9 is an enlarged perspective view of the male coupling loop.

Like characters of reference are used throughout the following specification and the accompanying drawings to designate corresponding parts.

In carrying out the invention, there is shown and provided an improved form and construction of car coupling including the cooperating draw heads generally designated by the reference numerals 1 and 2 respectively attached to the adja-

2

cent ends of the cars 3 and 4, which are shown as of the mine car type.

The draw head 1 attached to the end of the car 3 comprises the upper and lower jaw members 5 and 6 which are disposed in vertically spaced relation and between which the resilient U-shape guide plate 7 is secured by means of the bolt 8. The outer ends of the guide plate 7 are outwardly flared as at 9 and 10, being arcuately bent. Angle iron arcuate side guide members 11 and 12 are secured by the units 13 to the upper surface of the lower flared end 10 of the guide plate 7.

A transversely extending hinge bracket 14 is secured by the bolts 15 to the end of the car 3 and rotatably supports the central portion 50 of the release shaft which is provided with the depending actuating lever 16 on its outer end, and with the forwardly extending arm 17 at its inner end. Parallel ears 18 are formed in the outer end of the arm 17, and transversely aligned slots 19 are formed through said ears for receiving a cross bolt 20 which extends through the apertured upper end of the locking bar or rod 21 mounted for vertical movement through the bushing 22 supported between the L-shape arm 23 secured by bolts 24 to the end of the car 3 and the upper flared end 9 of the guide plate 7, and the lower end of said bar or rod 21 is adapted to pass through aligned openings 25 formed through the ends 9 and 10 of the guide plate 7 when two cars 3 and 4 are coupled together.

An L-shape angle stop bracket 26 is secured by the bolts 27 to the end of the car 3 directly above the forwardly extending arm 17 to limit the upward movement thereof.

A trip gate arm 28 is formed with a vertical central portion 29 rotatably mounted in the hinge bracket 30 secured by the bolts 31 to the end of the car 3, and is formed with an arcuate arm 32 having an L-shape trip gate head 33 on its outer end for positioning in vertical alignment with the openings 25 and for supporting the lower end of the locking bar or rod 21 when the coupling is not in use. A lower laterally extending arm 34 is formed on the gate arm 28 and is connected by the link 35 with one end of a bar 36 pivoted centrally upon the bolt 37 to the bottom of the car 3, and a second link 38 is connected between the opposite end of the bar 36 and a coil spring 39 anchored at 40 to the bottom of the car 3 for normally and resiliently holding the arm 36 and trip head 33 in its forward position.

The draw head attached to the end of car 55 4 comprises the upper and lower jaw members

41 and 42 which are disposed in vertically spaced relation. A supporting plate 43 is pivotally mounted upon the lower jaw member 42 upon the inverted L-shape pin 44 which extends through aligned openings 45 and 46 in said jaw members 41 and 42. An L-shape guard bracket 47 is secured by the bolts 48 to the end of car 4 directly above the upper end of the pin 44 to prevent accidental removal or the loss of the same. Oppositely disposed vertical guide flanges 49 and 50 are formed integral with the supporting plate 43 and extend upwardly at right angles thereto.

A double ended interconnected coupling member comprising links 51 and 52 is supported upon the plate 43 and held from removal by the pin 44, with the sides of the inner link 52 in engagement with the guide flanges 49 and 50. The adjoining ends of the links 51 and 52 are flat and are in contact with each other, being secured together by the bolt 53.

A bell-crank supporting and positioning lever 54 is pivoted at 55 to the bottom of car 4 and has its outer end offset and extending upwardly, terminating in a loop 56 disposed about the link 52, while the opposite end of the lever 54 is attached to one end of a coil spring 57 whose opposite end is anchored to a bracket 58 attached to the bottom of car 4. A spring clamp finger 59 is attached by the rivets 60 to the inner end of the link 51 for holding and reinforcing the coupling member when being coupled.

From the foregoing description, it will be apparent that when cars 3 and 4 are bumped together, they will be automatically coupled, and when they are to be uncoupled, it is only necessary for a brakeman to raise up on the lever 16 to raise the rod or pin 21 to permit the link 51 to pull free from the draw head on car 3.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention, what I

claim as new and desire to secure by Letters Patent of the United States is:

A coupling for mine cars, comprising a draw head embodying spaced upper and lower guide jaws of substantial widths having aligning openings formed therewith, a vertically novable coupling pin slideable through the aligning openings, a curved horizontally swinging trip gate arm pivotally mounted between said jaws, said gate arm having a wide flat head formed on the free end thereof, movable to a position between said aligning openings, a coiled spring having one end anchored against movement, connecting links between the other end of the spring and said trip gate arm normally biasing the gate head to a position directly under said coupling pin providing a support on which the coupling pin normally rests, a substantially large vertical flange rising from one edge of said gate head normally lying within the space between said jaws, and a cooperating draw bar having a link anchored thereto, adapted to move against said flange of the gate head, moving said gate head from a position under said pin when cars are being coupled, releasing said coupling pin, said coupling pin moving to a position within the link anchored to the draw bar, securing said link and draw head together.

NATHANIEL CLARK.
